UNITED STATES PATENT OFFICE

147,210

DESIGN FOR A CHILD'S ANIMAL TOY OR SIMILAR ARTICLE

George Winston, New York, N. Y.

Application May 16, 1946, Serial No. 129,755

Term of patent 3½ years

(Cl. D34—15)

To all whom it may concern:

Be it known that I, George Winston, a citizen of the United States of America, residing in the city, county, and State of New York, have invented a new, original, and ornamental Design for a Child's Animal Toy or Similar Article, of which the following is a specification, reference being had to the accompanying drawing, forming a part thereof.

Fig. 1 is a side elevational view of a child's animal toy or similar article showing my new design;

Fig. 2 is a front view thereof;

Fig. 3 is a sectional view taken on line 3—3 of Fig. 1; and

Fig. 4 is a back view of the animal toy.

I claim:

The ornamental design for a child's animal toy or similar article, as shown.

GEORGE WINSTON.
